UNITED STATES PATENT OFFICE.

GEORGE W. DITMORE, OF ALBANY, NEW YORK, AND CLIFTON W. SHERMAN, OF HAMILTON, ONTARIO, CANADA.

DRAFT YOKE.

Application filed September 6, 1924. Serial No. 736,210.

To all whom it may concern:

Be it known that we, GEORGE W. DITMORE and CLIFTON W. SHERMAN, citizens of the United States, residing at Albany, in the county of Albany and State of New York, and Hamilton, county of Wentworth, and Province of Ontario, Canada, respectively, have invented a new and useful Improvement in Draft Yokes, of which the following is a specification.

This invention relates to a draft yoke for railway cars of the type having longitudinal bars, a front pocket which receives the butt of the draw bar shank, an intermediate pocket which receives the front set of elements of the buffing mechanism, and a rear pocket which receives the rear set of elements of the buffing mechanism.

The object of this invention is to provide a draft yoke of this character in which the front parts of the longitudinal bars are securely connected and form a strong and durable pocket in which the enlarged butt of the draw bar shank may be mounted so as to be capable of being easily and readily mounted and dismounted in a direction transversely of the draft yoke; also to construct the longitudinal bars relatively to the front stop so that the buffing strains of the draw bar are transmitted to a large extent endwise to these bars and thereby relieve from shearing strains the pins which connect the draw bar shank with the draft yoke; and also to provide ribs on the longitudinal bars from the front ends thereof to the central stop for the purpose of strengthening the yoke and enabling the same to more effectively transmit buffing strains from the front parts of the longitudinal bars to the central stop and the rear buffing elements.

In the accompanying drawings:

Figure 1 is a side elevation of a draft yoke embodying our improvements.

Figure 2 is a top plan view thereof.

Figure 3 is a longitudinal section taken on line 3—3, Figure 1.

Figure 4 is a bottom plan view of the draft yoke.

Figure 5 is a side elevation viewed from the side opposite to Figure 1.

Figure 6 is a vertical section taken on line 6—6, Figure 5.

Similar characters of reference indicate like parts throughout the several views.

The numerals 10 and 11 represent the upper and lower longitudinal bars of the draft yoke which are associated with other parts to form a front pocket for the reception of the shank of the draw bar, an intermediate 60 pocket which receives the front section or set of elements of the buffing mechanism, and a rear pocket which receives the rear section or set of elements of the buffing mechanism.

The front parts of the longitudinal bars form the top and bottom of the front pocket. At the front ends of these bars is a pair of vertical lugs 12, 13 which project toward each other and form the front side 70 or wall of the front pocket, and an upright front stop 14 connects the bars at a distance rearwardly from the lugs and forms the rear wall or side of this pocket. In this front pocket is removably mounted 75 the shank of the coupler draw bar which has a reduced neck 15 arranged between the lugs 12, 13 and a vertically enlarged butt 16 at the rear end of this neck which is arranged in the front pocket and bears with 80 its rear side against the front stop 14 and provided with forwardly facing shoulders 17, 18 which engage with the rear or inner sides of the upper and lower lugs 12, 13. The butt of the draw bar shank is secured in this pocket by one or more headed pins 19, preferably two, passing vertically through corresponding openings in the butt and the front parts of the upper and lower bars and bearing with their heads against 85 the top of the upper bar and held against displacement by cotter or keys 20 passing through the pins below the underside of the lower longitudinal bar.

On one lateral side of the draft yoke the front pocket is entirely open so as to permit the free introduction of the coupler butt into this pocket as well as the removal of the same therefrom. The opposite lateral side of the front pocket is partly obstructed 100 or closed by two thick inner longitudinal ribs 40 arranged on the inner sides of the bars 10, 11 at one pair of corresponding longitudinal edges thereof and connecting the corresponding ends of the lugs 12, 13 with the respective vertical edge of the front stop 14. A thin upright longitudinal web 21 connects at its rear edge with the adjacent edge of the front stop 14 and at its upper and lower edges with the inner lon- 105 110

itudinal ribs 40, but the same is separated and wholly disconnected from the lugs 12, 13.

By this means the inner ribs 40 serve as a main stiffener which reinforces said lugs and front stop and enables the same to take the heavy strains to which they are subjected and a strong and durable connection is formed between the front parts of the bars and the front lugs thereof which effectually prevents the same from spreading under the strains to which the same are subjected while in use and at the same time leaving enough clear space immediately in front of the web through which a tool may be introduced into the front pocket for driving the butt of the draw bar out of the same in case it has a tendency to stick.

The intermediate pocket of the draft yoke is formed between the front stop and an upright central stop 22 which connects the central parts of the bars, and the rear pocket is formed between the central stop and an upright rear stop 23 connecting the rear ends of the bars.

In the intermediate pocket is arranged the front section or set of elements of the buffing or shock absorbing mechanism consisting, for example, of a front follower 24 engaging with the rear side of the front stop and adapted to engage with rearwardly facing stops or shoulders on the car sills, a front intermediate follower 25 engaging with the front side of the central stop and adapted to engage with forwardly facing stops or shoulders on the car sills, and a front spring 26 interposed between said followers. The rear pocket contains the set of elements of the rear section of the shock absorbing or buffing mechanism which may consist of a rear follower 27 engaging the rear stop 23 and adapted to engage forwardly facing stops or shoulders on the car sills, a rear intermediate follower 28 engaging with the rear side of the central stop 22 and adapted to engage with rearwardly facing stops or shoulders on the car sills, and a rear spring 29 interposed between the rear follower and the rear intermediate follower.

As shown in Figures 1 and 5, the distance between the inner sides of the longitudinal bar in front of the front stop is greater than the distance between the inner sides of the bars in rear of the front stop, thereby forming forwardly facing shoulders 30 on the inner sides of said bars which are vertically in line with the front side of the front stop. In consequence of this construction the upper and lower ends of the

enlarged butt, which is of substantially the same height as the front pocket engages with the front side of the front stop and also the inner shoulders 30 on the bars, thereby producing an endwise thrust against that part of the metal of the longitudinal bars in rear of the front stop and relieving the pins 19 from the load and shearing strains imposed upon them.

On the top and bottom sides of the upper and lower bars the same are provided adjacent to the longitudinal edges thereof with longitudinal ribs or flanges 31 which extend from the front ends of these bars to the central stop of the same, as shown in Figures 1, 2, 4 and 5. By this means these bars are stiffened or strengthened and enabled to transmit the shock during a buffing action from the draw bar to the rear section of the shock absorbing mechanism so that the load is divided between the same and the front section of the absorbing mechanism without liability of breaking or bending the draft yoke or making the same unduly heavy or expensive.

We claim as our invention:

A draft yoke comprising upper and lower longitudinal bars, vertical lugs arranged at the front ends of said bars and projecting toward each other, an upright stop connecting the longitudinal bars at a distance rearwardly from said lugs, thick inner longitudinal ribs arranged on the inner sides of said bars at one pair of corresponding longitudinal edges thereof and connecting the ends of said lugs with the corresponding vertical edge of said stop, and a thin web connecting said inner longitudinal ribs with said stop and spaced from said lugs, the space at the opposite longitudinal edges of the bars and stop being entirely open, thereby forming a pocket between the front parts of said bars, lugs, stop, inner ribs and web into which the enlarged butt of a draw bar shank may be introduced through said entirely open side thereof and engaged with its front and rear shoulders against the opposing sides of said lugs and stop, said inner ribs reinforcing said lugs and stop, said web holding said bars against spreading, and the space in front of said web permitting a tool to be engaged with said butt for driving the same laterally out of said pocket.

In testimony whereof we affix our signatures.

GEORGE W. DITMORE.
CLIFTON W. SHERMAN.
